STORE DISPLAY FIXTURE

Abraham Skler, Los Angeles, Calif.

Application May 22, 1934, Serial No. 726,878

5 Claims. (Cl. 312—140)

This invention relates to improvements in store display fixtures and belongs to the class of exhibition devices for display of various kinds of merchandise.

More particularly, this invention relates to improvements in holders or supports for partitions adapted to be arranged in pairs, one to support a partition at each end thereof, the support having portions which are slidable in channels formed in the edges of fixed members, whereby said pair, with the partition therebetween, may be moved and the location of the partition thus changed at will, as set forth in my copending joint application, Serial No. 15 547,646.

Among the objects of this invention are: to provide an improved form of partition holder which is so braced that it is stronger, and has a greater resistance to bending than any existing holder known to applicant; which has the sliding portions so formed that they will automatically anchor themselves in their cooperating grooves in whatever position they may be placed; which may be instantly unlocked for removal to a changed position at will; which partition holders will be simple in form and low in cost, preferably an integral stamped member of sheet metal.

Other objects will appear as this description 30 proceeds.

With the foregoing and other objects in view, the invention consists in the novel and useful formation, construction, interrelation and combination of parts, members and features, as well 35 as mode and methods of use thereof, all as hereinafter described, shown in the drawing and finally pointed out in claims.

In the drawing:

Fig. 1 is a vertical section through an assembly 40 of partitioned chambers showing a rear partition and a pair of transverse side partitions; the latter supported by the sliding supports.

Fig. 2 is a vertical section taken on line 2—2 in a plane transverse to that on which Fig. 1 45 is taken.

Fig. 3 is an isometric perspective of one form of partition support.

Fig. 4 is a front elevation of a modification of the support or a view from that side on which 50 the partition enters the jaws of the support.

Fig. 5 is a front elevation of another modification of the support.

In the figures, 12 and 13 form the two parallel sides and 14 the back connecting and supporting member of a channel or jaw which is

adapted to accommodate the edge of a partition member J. Rear member 14 of this channel extends longitudinally beyond the limits of the channel, and this member 14 spreads diagonally outward in each direction to greater width with increasing distance from the end of the channel, as shown. This member 14 is, therefore, widest at the bottom 17—17 and narrowest at zone 15—15 just at the beginning of the jaw sides 12 and 13. The wide end 17—17 is bent at right angles to the surface of plate 14 to form a slide member 18 adapted to work in a groove 22, which latter is formed in the edge of the lower horizontal boards D, which boards constitute the bottoms of the compartments, the 15 sides whereof are formed by the movable partitions J cooperating with other partitions H transverse thereto. Partitions J are carried by the paired members described and shown and by sliding the projecting part 18 in the slots 22, 20 the partitions J may be moved to any preferred position and the width of the compartment correspondingly changed. But, unless some means of anchorage is provided, any slight force will move the partitions J and the sliding supports. 25

Since the partitions J are usually thin, being preferably of glass, the section of the back member 14 is comparatively narrow at the zone 15—15 and, being usually made of thin metal, the usual forms of supports may be easily bent in a direction transverse to the plane of member 14. Hence, in order to strengthen this improved holder, diagonal bracing gussets 10 and 11 are provided which are continuations of jaw sides 12 and 13 respectively, and these braces merge into the rear flat plate member 14 as depicted. 30 35

An effective form of anchorage to hold the support members from sliding in the edge grooves or slots 22 is provided by bending or bowing part 18 longitudinally so that it is not flat but is curved between its ends as shown in the figures, the ends presenting sharp edges 19—19 to the surface of the groove 22 and the height of the camber being such that part 18 extends across the width of the groove 22, which causes 40 the upper surface of member 18 to press against the upper surface of groove 22 while the lower sharp edges 19—19 ride against the lower surface of groove 22. Since the grooves 22 are usually formed in wooden members, the edges 19—19 45 will cut into the material and thereby anchor the support member. By lifting upward, and thereby compressing the upper bent portion of part 18, thereby raising an end 19 from the groove bottom, the support member slides easily 50 55

in its groove and when released again anchors itself, by a sharp end 19 cutting into the surface of the groove.

Obviously, the form of the slide member 18 may be changed so that it is bent to curve upward as shown in Fig. 4, instead of downward as depicted in Fig. 3. Also, the member 18 may extend past the gusset plate 14 at each end as shown in Fig. 5 instead of being limited in length to the width of plate 14, as shown in Fig. 3. In fact this last form seems to provide somewhat better "spring" or elasticity than these forms in which slide member 19 is coextensive with the end of plate 14.

Having described my invention in connection with illustrative embodiments, forms, proportions and arrangements of parts, it will be understood that many variants thereof are possible to those skilled in the art, and my invention, in its broader aspects, is not limited to the specific construction herein described and shown, as changes in the sizes, proportions, configurations, arrangements, assemblage, interaction, juxtaposition and mechanical relations, as well as additions, omissions, substitutions, combinations and alterations of forms, parts, members and features, may be made without departing from the broad spirit of this invention.

Having thus disclosed my invention, I claim and desire to secure by Letters Patent:

1. In a sliding support for partitions, the combination of a support plate having a channel at one end thereof for reception of a partition edge, a slide portion at the opposite end of said plate adapted to work in a groove, said groove being perpendicular to the surface in which it is formed and said slide being bent along its length to extend across the groove width.

2. A sliding partition support of the character disclosed having a channel for reception of a partition edge attached to one end of a support plate and gusset extensions of the walls of said channel connected with said support plate, a slide portion at the end of said plate opposite to the channel portion and adapted to work in

a groove, said slide portion being perpendicular to the surface of the plate and extending along said plate end, and being bent transversely along its length, to provide resilient compression contact against opposite faces of said slot.

3. In combination, a bottom planar member having a groove in an edge thereof, a partition adapted to be adjustably movable over said bottom member, a partition support comprising a vertical plate having an end bent into a horizontal plane adapted to work in said groove, a partition-receiving channel near the opposite end of said plate, bracing means between said channel walls and said vertical plate, and anchoring means for said bent portion working in the groove comprising an end of said portion bent to extend across said groove.

4. In a support of the character disclosed, a slide portion adapted to move in a groove, the thickness of said portion being less than the width of said groove, said slide portion being bent longitudinally whereby its ends are adapted to press against one surface of the groove while a part intermediate its ends is adapted to press resiliently against the opposite surface of said groove.

5. In a device of the character described, the combination of a bottom planar member, having a groove in an edge thereof perpendicular to the surface of said edge; a partition adapted to be adjustably moved over said bottom member, a partition support comprising a member having a longitudinal portion adapted to work in said groove and an extension therefrom having a partition-receiving channel therein, the channel being substantially normal to the longitudinal portion, and resilient means for anchoring said partition support in the groove comprising distortion of said longitudinal part along its length whereby a portion of said member is caused to exert pressure against one surface of the groove and another portion thereof is caused to exert pressure against the opposite surface of the groove.

ABRAHAM SKLER.
